REVOLVING PNEUMATIC GUN.

No. 399,882.

Patented Mar. 19, 1889.

UNITED STATES PATENT OFFICE.

JAMES WEIR GRAYDON, OF WASHIINGTON, DISTRICT OF COLUMBIA, ASSIGNOR
TO ROBERT SOUTHWORTH LAWRENCE, OF LONDON, ENGLAND.

REVOLVING PNEUMATIC GUN.

SPECIFICATION forming part of Letters Patent No. 399,882, dated March 19, 1889.

Application filed November 8, 1888. Serial No. 290,289. (No model.)

To all whom it may concern:

Be it known that I, JAMES WEIR GRAYDON, a citizen of the United States of America, residing at Washington, in the District of Columbia, have invented certain new and useful Improvements in Revolving Air-Guns, of which the following is a specification, reference being had therein to the accompanying drawings.

10 My invention relates to a revolving air-gun for throwing dynamite or other high-explosive projectiles; and its object has been the production of a gun in which, by the simple turning of a crank, the projectiles may be automatically placed in the barrels, the barrels revolved, and the projectiles discharged under a predetermined regulated degree of air-pressure.

15 The invention will first be described in connection with the accompanying drawings, and then clearly pointed out in the claims.

Figure 1 of the drawings is a longitudinal section of the gun, taken on the line $x x$, Fig. 3, the reservoir and the air-pressure regulator being shown in side elevation. Fig. 2 is a longitudinal section of the gun, taken on the line $y y$, Fig. 3, and a diagram of the reservoir and air-pressure regulator. Fig. 3 is a transverse section of the gun, taken on the line $z z$, Fig. 1, showing the loading, revolving, and discharging mechanisms. Fig. 4 is a horizontal section of the air-pressure regulator. Fig. 5 is a sectional detail showing the two-way cock in the pipe connecting the reservoir and regulator.

30 Referring to the drawings, A represents the breech-piece, provided at its rear end with a door, a .

B is the frame of the gun.

35 $C C'$ are the assembling-disks.

D is the main shaft, which passes through the disks, and is rigidly secured thereto, it being loosely journaled at its front end in the frame and at its rear end in the breech-block.

40 E represents the barrels, preferably five in number, which are mounted in and carried by the assembling-disks, the rear ends of the barrels being screwed into the disk C .

45 The mechanism for revolving the barrels is as follows: F represents the pin-wheel, consisting of a short cylinder having a series of

pins or projections, 1 2 3 + 5, (corresponding in number with the number of barrels,) on one end. This is rigidly secured on the rear end of the main shaft D , with the pins to the rear.

55 G represents a worm-wheel located in the breech-piece in rear of the pin-wheel, and mounted on a shaft, H , journaled in one side of the breech-piece and also in a standard, I , inside the breech-piece. The worm on the wheel G is of the same width for about three-fourths the circumference of the wheel, and then gradually narrows down and flares outward to the sides, leaving a groove, 6 , as seen in Fig. 3, and the worm-wheel is so positioned with relation to the pin-wheel that only the lower pin will engage with the groove. The worm-wheel is revolved by means of a crank-handle, h , on shaft H .

60 The loading mechanism will next be described.

65 In the upper portion of the breech-piece there is formed a channel or guideway, b' , part of which is open, as at b^2 , and above this open part of the channel is located a magazine, J , for containing the projectiles j , as seen in Figs. 2 and 3. In this channel, directly in front of the open part, is located a loading-piston, K , for pushing the projectiles into the barrels, the piston being provided on one side with a stud, k , which passes through a slot, s , in one of the side walls of the guideway b' , as seen in Fig. 3. A gear-wheel, w , on the inner side of shaft H , meshes with another gear-wheel, w' , on a short shaft, S , journaled in standard I and in the side of the breech-piece, and on this shaft is secured a cam, S' , which works within a link, L , which is pivoted at its lower end to the bottom of the breech-piece. This link is provided with an arm, l , whose upper end passes loosely through an opening in stud k , as seen in Fig. 3.

70 A description of the pneumatic mechanism is now in order.

75 M represents the air-reservoir, which is a steel cylinder mounted in any suitable framework (not shown) connected with the gun proper, and M' is a pipe leading from any suitable air-pump (not shown) to the reservoir. I have illustrated but one reservoir, although more may be employed, if desirable,

and be in communication with each other by means of connecting-pipes.

N represents the casing of the air-pressure regulator, constructed of iron or steel plates bolted together.

O is a rectangular box located inside casing N, at its rear end, and the interior of which constitutes the air-chamber O'; and P indicates a pipe leading from the reservoir M to said chamber. This pipe is provided with a two-way cock, P', operated by an eccentric-rod, P², connected thereto and to the shaft H, for admitting air from the reservoir to the air-chamber, and also for shutting off the air from the reservoir and permitting the escape of so much of it, through a discharge-opening, o, in the pipe, as will be sufficient to allow spring W to again open the valve, as will be more fully explained hereinafter.

V represents the valve-chest, located in one corner of casing N, the said chest being square and provided centrally with bearings v for the valve-shaft.

V' indicates the valve, which consists simply of a plain metal plate neatly fitting the interior of chest V and carried by a shaft, V², journaled in the bearings v in the chest. The plate forming the valve passes through a slot in the shaft, and is held in place therein by means of screws 7. When open, as in Fig. 4, the valve lies horizontal, and its under side rests on lugs 8, cast inside the valve-chest at one end, while its upper side rests against other lugs, 9, cast in the chest at the other end.

A pipe, R, screwed through the front wall, near the rear end of box O and through the adjacent wall of the valve-chest, slightly above the valve, when in its open position, connects the air-chamber O' and the valve-chest, and another pipe, R', leads from said chest forward to the inner side of the air-reservoir, and thence out through the top of the reservoir, its outer end being screwed into the under side of the breech-piece of the gun in line with an air-duct, R², leading to the front face of the breech-piece, with which duct the bore of the lower barrel of the gun registers. There is an elastic packing, 10, set in the front face of the breech-piece and surrounding the outer end of duct R², for the purpose of forming a tight joint between the barrel and breech-piece, as seen in Fig. 1.

T represents a cylinder, the open front end of which is screwed into the front wall of the air-chamber O' flush with the inner side thereof. In this cylinder is located a piston, T', secured to one end of a piston-rod, T², whose other end is pivotally connected at t 60 to an arm, V³, journaled on a crank-arm, V⁴, secured on valve-shaft V².

U is a beveled gear-wheel secured on a hollow arbor, U', located in the end wall of cylinder T. That portion of the arbor within said wall is screw-threaded exteriorly to engage with an interiorly screw-threaded thimble, U², rigidly secured to a perforated disk,

U³, within cylinder T, and a coiled spring, W, encircles the piston-rod T² between this disk and the piston the piston-rod passing through the disk, the arbor, and the gear-wheel U. An annular groove, u, is cut in the arbor, into which depends a flange, f, from the end wall of cylinder T, to prevent longitudinal movement of the arbor. The said bevel-wheel U gears with another bevel-wheel, U⁴, mounted on a short shaft, U⁵, journaled in one of the side walls of the regulator-casing N, which shaft bears on its outer end a crank-handle, X, and on the outer side of casing N, just outside the arc described by the crank-handle, there is a segmental scale of figures to indicate the different degrees of pressure to which the regulator may be set.

It is to be understood that the above-described air-pressure regulator is not claimed specifically herein, but only in combination with other elements embodied in the revolving gun, said regulator itself forming the subject-matter of another application for Letters Patent of the United States, Serial No. 287,627, filed by me on the 9th day of October, 1888.

The operation of my revolving air-gun is as follows: The magazine being filled with shells and one of the barrels loaded, as seen in Fig. 2, then on turning the shaft H one of the pins on the pin-wheel F will engage the groove 6 in the worm on wheel G and be moved to the opposite side of the worm, thus turning the barrels one space. As the worm is straight for the greater portion of its circumference, the pin-wheel and the barrels will remain stationary, while the pin follows that portion of the worm, thus affording time for loading and discharging the gun. An empty barrel being now presented to the loading device and another shell having dropped from the magazine into the guideway b', the continued revolution of shaft H will cause the cam S', through the medium of gear-wheels w w' and shaft S, to turn in the link L and rock the link forward, when the arm l of the link will carry the loading-piston and the projectile in the guideway forward far enough to place the latter within the barrel, the loading-piston being drawn back to its former position on further revolution of the cam, when another projectile will drop by gravity into the guideway, and so on. In the revolution of the shaft H the eccentric-rod P² is caused to operate the two-way cock P' to admit air from the air-reservoir to the gun at proper intervals. Now we will suppose that it is desired to discharge the projectile under an air-pressure of five hundred pounds to the square inch, which in the illustration is the minimum pressure denoted on the scale, and that the spring W is of such tension as to be compressed just at that pressure. Then it will be evident that the spring will hold the valve V' open, as seen in Fig. 4, until the air-pressure against the projectile in the gun shall have reached five hundred pounds, when that pressure will force the piston T' backward against the ten-

135

sion of the spring, which action, through the instrumentality of the piston-rod T^2 , arm V^3 , and crank-arm V^4 , will rock the valve-shaft and close the valve V' by turning it up into a vertical position in the valve-chest. Of course the projectile will commence moving before the pressure runs up to five hundred pounds, but the increase of pressure will be so rapid that the maximum will be reached almost instantly. As soon as the gun is discharged and the valve closed, the two-way cock P' is turned to the position shown in dotted lines in Fig. 5, which cuts off communication between the reservoir and the valve and at the same time permits the escape from the air-chamber C through the discharge-opening o of a sufficient quantity of air to allow the spring W to again open the valve. As the valve when closed presents the same superficial area on each side of its shaft, the air-pressure against it must necessarily be the same below the shaft as above it, and consequently the valve will be balanced. Again, we will suppose that the air is to be admitted to the gun at a greater pressure than that above stated—say two thousand five hundred pounds to the square inch. In this case I turn handle X around until it registers with the figures 2,500 on the scale, and in thus turning it I also, through gear-wheels U^4 and U , turn arbor U' , which tends to screw thimble U^2 outward, the arbor being prevented from moving longitudinally by the engagement of flange f of the end wall of cylinder T with the annular groove u in the arbor. This outward movement of the thimble, and consequently of disk U^3 , compresses spring W between the disk and piston T' to an extent sufficient to require a pressure on the piston of two thousand five hundred pounds to the square inch to overcome the tension of the spring. This being done, the operation of the valve in other respects is the same as that above described.

Having thus fully described the construction and operation of my invention, what I claim as new, and desire to secure by Letters Patent, is—

1. The combination, with the series of revolute barrels, the breech-piece having a duct in register with one of said barrels when the latter is in position for discharge, and mechanism for revolving the barrels, of an air-reservoir, an automatic air-pressure regulator, a pipe provided with a shut-off cock, connecting the reservoir and regulator, and a pipe leading from the regulator to the duct in the breech-piece, whereby one of the barrels is discharged when the air exerts a predetermined degree of pressure in the regulator.

2. The combination, with the series of revolute barrels, the breech-piece having a duct

in register with the lower barrel when the latter is in position for discharge, and mechanism for revolving the barrels, of an air-reservoir, an automatic air-pressure regulator, a pipe provided with a shut-off cock, connecting the reservoir and regulator, and a pipe leading from the regulator into and out of the reservoir and connecting with the duct in the breech-piece, whereby the lower barrel is discharged when the air exerts a predetermined degree of pressure in the regulator.

3. In a revolving air-gun constructed substantially as described, the combination, with the worm-wheel shaft, the reservoir, the automatic air-pressure regulator, and the pipe connecting the reservoir and regulator, of a shut-off cock in said pipe, and an eccentric-rod journaled on the worm-wheel shaft and connected to said cock, whereby air is admitted to the regulator from the reservoir in proper relation to the loading and revolving operations.

4. The combination, with the breech-piece provided with a guideway in its upper portion, and a loading-piston in said guideway, of a link pivoted to the lower portion of the breech-piece and provided with an arm which engages with the loading-piston, a cam within the link, and mechanism for revolving the cam to rock the link, whereby the loading-piston is reciprocated in the guideway, for the purpose set forth.

5. The combination, with the breech-piece provided with a partially-open guideway in its upper portion, a magazine above the open part of the guideway, and a loading-piston in said guideway, of a link pivoted to the lower portion of the breech-piece and provided with an arm which engages with the loading-piston, a cam within the link, and mechanism for revolving the cam to rock the link, whereby the loading-piston is reciprocated in the guideway, for the purpose set forth.

6. The combination, with the breech-piece provided with a guideway in its upper portion, and a loading-piston in the guideway, of the worm-wheel shaft journaled in the breech-piece and provided on its inner end with a gear-wheel, a link pivoted in the lower portion of the breech-piece and having an arm in engagement with the loading-piston, a short shaft journaled in the breech-piece and carrying a gear-wheel in mesh with the one on the worm-wheel shaft, and a cam within the link secured on said short shaft, substantially as described, and for the purposes stated.

In testimony whereof I affix my signature in presence of two witnesses.

JAMES WEIR GRAYDON.
